RECORDING HEAD

Carl Leeb and Morris A. Gilman, Chicago, and
Carl Anderson, Oak Park, Ill., assignors to
Actino Laboratories, Inc., a corporation of Illinois

Application June 3, 1939, Serial No. 277,272

7 Claims. (Cl. 179—100.41)

This invention relates to a recording head.

An object of the invention is to provide a much simpler structure which is extremely sturdy and adapted for long use. A further object is to provide a recording head which is faithful and accurate in recording operations and which may be constructed of very few parts. A still further object is to provide a recording head which does not deteriorate except after extremely long periods of usage, and which avoids the use of rubber and like materials which deteriorate rapidly in time. Other specific objects and advantages will appear as the specification proceeds.

The invention is illustrated, in a preferred embodiment, by the accompanying drawing, in which—

Figure 1 is a side view in elevation of a recording head embodying my invention; Figure 2, a longitudinal sectional view, the section being taken as indicated at line 2 of Figure 3; Figure 3, a sectional view, the section being taken as indicated at line 3 of Figure 1; Figure 4, a sectional view, the section being taken as indicated at line 4 of Figure 3; Figure 5, a transverse detailed sectional view, the section being taken as indicated at line 5 of Figure 4; Figure 6, a bottom plan view of the spring plate or fulcrum employed; and Figure 7, a broken sectional view showing the method of attachment of the armature to the spring plate.

In the illustration given, 10 designates a metal casing in which the parts are housed. A supporting metal plate 11 is secured to the back of the housing and a permanent magnet 12 in the shape of a horseshoe is confined against plate 11 by an outer plate 13 and screw 14. Secured to plate 11 by welding, or other suitable means, are the field metal pieces 15 which provide between them a chamber for the coil 16. The coil 16 is supported between two insulating paper strips 17 and 18. Wires 19 extend through the top of the casing and connect their inner ends with the coil 16.

The field pieces 15 have horizontal flanges 20 which are slightly spaced apart and provide an opening through which the armature 21 extends into the space between the arms of the magnet 12.

To the lower ends of the field pieces 15 are secured the ends of a metal spring plate 22. In order to secure the armature 21 to the spring 22 in a permanent manner, and while adding a minimum of weight to the armature, we employ the following extremely satisfactory method. The armature 21 is provided at its lower end

with a tubular portion 23, and this, after the armature is in position, is spun over an angular piece 24 to form the permanent anchorage illustrated in Figure 7. It will be observed that the armature 21 is provided above the spring with an enlarged body portion 25 which has at its bottom a shoulder bearing against the spring plate 22. By bending over the tubular portion 23 in connection with the collar of the member 24, an extremely sturdy and permanent connection is made while at the same time adding very little weight to the armature. It will be noted that the member 24 has a horizontal flange portion which rests against the bottom of the plate 22 and then at its inner end a depending collar portion about 15 which the flange 23 of the armature is spun.

The armature 21 is provided with the usual slot 26 adapted to receive the cutter pin 27 and the cutter is locked in position by the threaded handle member 28.

The casing 10 is provided with a bottom plate 29 provided with a relatively large opening 30 through which the cutter pin 27 freely extends.

Operation

In the operation of the device, current passes through the two wires 18 leading from the sound actuated source and flows through the coil 16. The magnetic field produced in response to the irregularities of the current causes the upper portion of the armature to swing laterally. The flexible spring 22 serves as a fulcrum upon which the armature and pin swing so that the point of the pin, in traversing the recording means, moves laterally in the longitudinal track thereon. In this operation, it will be observed that the armature 21 is integrated through the connections described with the spring plate 22 and that the plate serves as a support as well as a fulcrum for the armature. The result is a faithful recording of the sound upon the record.

It will be observed that the structure is extremely simple and sturdy, consisting of few parts which can be readily assembled. Deteriorating parts heretofore employed are avoided. The fulcrum and dampening material, employed in the recording heads largely used today and which are made of elastic material such as rubber which deteriorates under weather conditions after a relatively short period of time, are eliminated while at the same time a recording head is produced which is believed to be more accurate in operation.

While we have described the structure in detail, it will be understood that the details are

given for the purpose of setting forth a clear modification employing the invention and that such details may be varied widely by those skilled in the art without departing from the spirit of our invention.

We wish it to be understood that we do not desire to be limited to the exact details of construction shown and described, for obvious modifications will occur to a person skilled in the art.

10 We claim:

1. In a recording head, a frame, means responsive to variations in an electric current for varying a magnetic field, a spring plate member carried in said frame, an armature fulcrumed upon said spring member and supported thereby within said field for lateral pivotal movement, and a cutter member secured to said armature.

2. In a recording head, a frame, a flat spring supported by said frame, an armature secured to said spring, means responsive to variations in current for varying the magnetic field about the upper portion of said armature to produce lateral movement thereof, and a cutter member secured to the lower portion of said armature.

25 3. In a recording head structure of the class set forth, a casing, a permanent magnet secured within said casing, a flat spring supported below said magnet with the central portion of the spring free for movement, an armature having its lower portion rigidly secured to and fulcrumed upon said spring and having an upper portion extending through a coil into a magnetic field, electric connections to said coil, and a cutter member secured to said armature.

30 4. In a structure of the class set forth, a frame, a flat spring supported therein at its ends, means responsive to variations in an electric current for varying the magnetic field therein, an armature having its upper portion extending into said

40 magnetic field and having its lower end portion

extending through an opening in said spring, a collar below said spring, the lower end of said armature being spun about said collar, said armature having a shoulder on the side opposite said collar engaging said spring whereby said 5 armature is fixedly secured to said spring.

5. A method of assembling an armature provided with a hollow lower portion and with a shoulder to a flat spring comprising perforating the spring and passing the lower end of the 10 armature therethrough until the shoulder of the armature rests against the spring, inserting a collar member over said hollow end of the armature and against said spring, and then spinning the hollow portion of the armature about said 15 collar.

6. The method of forming a lightweight armature and flat spring connection comprising: perforating a flat spring, extending an armature having a shoulder thereon through said spring 20 until the shoulder rests thereon, inserting a washer member over said armature and against the bottom portion of said spring, said washer having a depending collar, and spinning the lower portion of the armature about said collar. 25

7. In a recording head of the class set forth, a casing, a permanent magnet secured therein, field pieces secured below said magnet, a coil supported between said field pieces and provided with electric wire connections, a flat spring having its ends secured to the field pieces and having a flexing portion therebetween, an armature extending between said field pieces and through said coil, said armature having its lower portion extending through and secured to said spring, 30 and a cutter member secured to said armature.
